United States Patent Office

Des. 203,613
Patented Feb. 1, 1966

203,613

COOKING VESSEL OR THE LIKE

James L. Hvale, Chicago, and Benjamin N. Yamada, Melrose Park, Ill., assignors to Club Aluminum Products Company, La Grange Park, Ill., a corporation of Illinois

Filed Dec. 2, 1964, Ser. No. 82,888

Term of patent 14 years

(Cl. D44—1)

Fig. 1

Fig. 2

Fig. 3

FIGURE 1 is a perspective view of a cooking vessel or the like in the form of a saucepan having a cover, showing a new design;

FIG. 2 is a top plan view of the vessel of FIG. 1;

FIG. 3 is a partially broken away side elevational view of the vessel of FIG. 1;

FIG. 4 is a bottom plan view of the vessel of FIG. 1;

FIG. 5 is a perspective view of a cooking vessel or the like in the form of a frypan having a cover showing a new design;

FIG. 6 is a top plan view of the vessel of FIG. 5.

FIG. 7 is a side elevational view of the vessel of FIG. 5; and

FIG. 8 is a bottom plan view of the vessel of FIG. 5. We claim:

The ornamental design of a cooking vessel or the like, substantially as shown and described.
